HEATER

Edwin Esson, Kansas City, Mo., assignor to Locke
Stove Company, Kansas City, Mo., a corpora-
tion of Missouri

Application September 19, 1941, Serial No. 411,535

7 Claims. (Cl. 126—73)

This invention relates to heaters for burning solid fuels, and has for its principal object to provide a heater of the magazine type constructed for more efficiently controlling combustion and to avoid overheating parts thereof which ordinarily reduce the life of such heaters.

Another object of the invention is to provide a heater having a modern, rectangular exterior and a substantially cylindrical fuel magazine arranged to provide flue ducts in the corners of the heater through which products of combustion are discharged from the fire-pot and in which burnable gases are consumed prior to discharge into a chimney.

A further object of the invention is to provide a grate basket structure designed for adequate support of the refractory liners which form the sides of the fuel magazine and to provide the grate basket with outlets to the respective corner flues.

Other objects of the invention are to provide a heater with an air chamber surrounding the grate basket and provided with an inlet for secondary air separate from the primary air inlet for the heater; to provide the heater with up-draft air ducts connecting the secondary air supply chamber with outlet ends of the flue ducts for supplying secondary air to support combustion of any smoke particles or unconsumed burnable gas discharged from the upper end of the flue ducts; to provide the secondary air ducts in heat exchange relation with the flue ducts to reduce temperature of the flue ducts and further preheat the secondary air; to provide the grate basket with means for passing air over the outlets to the flue ducts for cooling supports which carry the refractory liners; to provide for discharging such air into the lower ends of the flue ducts thereby insuring thorough combustion; to provide a movable vane for controlling inlet of air to the secondary air chamber which is adapted for automatic operation responsive to the amount of draft through the flue ducts; to provide the upper portion of the magazine with guards for preventing clogging of the flue ducts incidental to filling the magazine and which serve as a support for holding the refractory liner in place and insure thorough mixture of the flue gases; and to provide the heater with a removable ash-pan provided with side rails to retain the ash-pit door in horizontal open position during withdrawal of the pan, thereby facilitating removal of the ashes.

In accomplishing these and other objects of the invention, as hereinafter pointed out, I have

provided improved details of structure, the preferred forms of which are illustrated in the accompanying drawings, wherein:

Fig. 1 is a perspective view of a heater constructed in accordance with the present invention, a portion of the side walls being broken away to better illustrate the fuel magazine, corner flues, and updraft ducts.

Fig. 2 is a vertical section through the heater.

Fig. 3 is a section transversely of the section shown in Fig. 2.

Fig. 4 is a vertical section through one side of the heater taken on a plane extending through a corner of the heater.

Fig. 5 is a detail perspective view of the fuel guard and mixing baffle.

Fig. 6 is a fragmentary perspective view of one corner of the grate basket illustrating the flue duct passageway and showing the bridge member for supporting the refractory lining thereabove.

Fig. 7 is a horizontal section through the heater on the line 7—7 of Fig. 2.

Fig. 8 is a similar section on the line 8—8 of Fig. 2.

Fig. 9 is a horizontal section on the line 9—9 of Fig. 2.

Fig. 10 is a fragmentary perspective view of the heater showing the refractory lining removed to better illustrate the grate basket construction and its connection with the updraft ducts.

Referring more in detail to the drawings:

1 designates a heater constructed in accordance with the present invention and which includes an outer, shell-like body 2 having side walls 3—4 and front and back walls 5—6 interconnected at the corners on rounding curves 7. The lower portion of the heater body terminates in an inwardly extending, perimetrical flange 8 for support upon a base 9 to space the bottom 10 of the heater from the floor and provide for air circulation thereunder. The bottom 10 is supported on the flange 8 and cooperates with a grate basket assembly 11 to form a combined ash-pit and primary air chamber 12 therebetween. Formed in the front 5 of the heater is a door opening 13, of sufficient dimensions to permit insertion and removal of an ash-pan 14 to and from the ash-pit. The opening 13 is provided with a frame 15 having a door 16 hinged along the upper portion thereof as indicated at 17 so that the door swings downwardly and is normally retained closed incidental to weight thereof.

Formed in the front of the door is a primary air intake opening 18 for admission of primary air into the ash-pit to support combustion of the

fuel carried in the grate basket assembly. In order to facilitate removal of the pan the sides thereof are provided with guard rails 19 which are adapted to hold the ash-pit door 16 in horizontally open position during removal or insertion of the pan, thereby facilitating manipulation of the door while removing the ashes.

The grate basket assembly includes a substantially rectangular frame 20, inset within the heater body and engaging the walls thereof as best shown in Figs. 3, 4 and 10. The upper portion of the frame is provided with inwardly extending flanges 21 which seat a plate-like rim 22 of a fire-pot 23. The rim or plate portion 22 has the corners thereof provided with angle-shaped notches 24 for discharge of secondary air from a secondary air chamber 25 that is formed between the plate portion 22 and a lower plate 26 which is inset within the lower portion of the frame 28, as best shown in Figs. 3, 4 and 10. The wall portion 27 of the fire-pot has its lower end extending through the plate 26 in completing closure of the secondary air chamber. Air is admitted to the secondary air chamber through a collar-like inlet 28 projecting through the rear wall of the heater and which is provided with a damper 29 adapted to control inlet of secondary air responsive to draft as later described.

The damper 29 is of the butterfly type and is pivoted in opposite sides of the collar 28 on trunnions 30. The damper is normally retained in closed position responsive to a weight 31 that is attached to the lower portion thereof as shown in Fig. 2. Closure of the damper may be adjusted by a screw 32 so as to assure an adequate amount of air under minimum draft conditions. The weight 31 is also preferably adjustable so that it may be set to maintain a predetermined pressure differential in the secondary air chamber responsive to draft through the heater.

The lower portion of the wall 27 terminates in inwardly extending fingers 33 supporting a shaker type grate 34 having openings 35 therethrough for passage of ashes from the fire-pot into the ash-pit and for admission of primary air 45 from the ash-pit into the fire-pot to support primary combustion of the fuel therein.

Formed in the corner of the plate portion 22, and opening through the wall portion 27 of the fire-pot, are grate basket flues 36 for directing products of combustion from the fire-pot upwardly through flue ducts 37 formed in the respective corners of the heater in inwardly spaced relation from the angle-shaped openings 24, previously referred to. Supported upon the plate portion of the grate basket assembly, intermediate the grate basket flues, are vertically arranged refractory tile liners 38, having flat rear faces 39 contacting the inner faces of the heater walls and of a width to extend between the terminal ends of adjacent angle-shaped openings 24. The tiles have flat side edges 40 adapted to abut against inturned flanges 41 of angle-shaped partitions 42. The angle-shaped partitions have their lower ends seated upon the plate portion 22 of the grate basket assembly intermediate the openings 24 and grate basket flues 36 and are of length to extend to the top of the heater body for cooperating with the corner of the heater body to provide updraft ducts 43 for conveying secondary air from the secondary air chamber to the upper portion of the heater. From the sides 40, the tiles converge inwardly, as at 44, and then outwardly at a lesser angle, as at 45, to form substantially V-shaped grooves 46. The inner faces

47 are of arcuate cross-section to cooperate with arcuate faces 48 of intermediate tiles 49 in forming a substantially cylindrical fuel magazine 50. The intermediate tiles have sides 51 formed to fit within the V-shaped grooves 46 of the adjacent tiles and have flat rear faces 52 subtending the legs of the angle-shaped partitions to form substantially triangular-shaped flue ducts 53 therebetween which connect the grate basket flues 10 with the upper portion of the heater.

The refractory tiles may be formed in upper and lower courses 54 and 55 to facilitate manufacture and handling thereof and the adjacent side edges of the intermediate tiles at the abutting ends thereof are provided with notches 56 which, when the tiles are in assembly, form slots 57 connecting the central portion of the fuel magazine with the flue ducts 53, the slots forming openings for discharge of gases evolved incidental to coking of the fuel and to assure burning thereof within the flue ducts as later described.

In order to protect and adequately support the lower ends of the intermediate tiles where they extend across the grate basket flues, I provide bridge members 58, having their ends supported in recesses 59 and 60 formed in opposite sides of the grate basket flues. The bridge members are of trough-like shape to form air passageways 61 having connection with the secondary air chamber through registering openings 62 formed in the side walls of the grate basket flues.

In order to assure circulation of air therethrough, the sides of the bridge members have nozzle-like outlets 63 extending into the flue ducts whereby the draft created therein effects an induced flow of air through the bridge members. This air is also used to aid in supporting combustion of smoke and burnable gases entering the flue ducts.

Carried upon the body of the heater is a dome-like top 64, having a perimetrical flange 65 engaging over the side walls and which is provided with an inset door opening 66 through which coal is supplied to the magazine. The opening is closed by a door 67 suitably hinged along the top edge of the opening and is provided with a handle by which it is readily moved to and from open position. Also formed in the top 64, at the rear thereof, is a collar 68 adapted to be connected with a vent pipe 69 leading to a chimney (not shown) for venting the spent products of combustion.

In order to assure thorough mixture of the secondary air with the gases and smoke particles that may be discharged from the upper ends of the flue ducts and to provide guards for preventing fuel from clogging the respective ducts, the top of the magazine carries a guard member 70, best illustrated in Fig. 5, which includes a substantially circular band 71 spaced from the side walls of the dome-like top to form passageways 72 therebetween, and which is provided with a plurality of slot-like openings 73 which connect the passageways 72 with the upper portion of the magazine and vent pipe 69. The guard 70 is further provided with trough-like bracket portions 74 and 75, which bear upon the upper edges of the tile linings immediately under the door opening and vent respectively, as best shown in Fig. 2. The guard thus prevents any fuel being discharged into the magazine from lodging in the ducts and provides protection for the liner at the point where the fuel is admitted. The 75 guard also acts as a baffle to assure thorough

mixture of the secondary air with the flue gases so as to effect ignition of any burnable gases before discharge through the vent, as well as gases arising directly through the magazine.

Assuming that the heater is constructed and assembled as described, a fire is kindled in the fire-pot portion of the grate basket assembly and the magazine is filled with fuel by way of the door 67. The fuel in the fire-pot burns and effects coking of the fuel immediately thereabove so that the evolved gases are discharged outwardly through the slot-like openings 57 of the liner where they come into contact with air admitted through the primary air inlet 18 into the ash-pit through the grate and into the flue ducts. Burning of the fuel in the fire-pot is also supported by this passage of primary air and the flow is responsive to chimney draft. The products of combustion are drawn through the grate basket flues into the vertical ducts and are discharged into the passageways 72 where they mix with the secondary air drawn through the updraft ducts 43 to assure combustion of smoke particles and any of the burnable gases prior to discharge through the vent pipe. The secondary air supply at the top of the heater is also sufficient to support combustion of any gases moving directly through the bed of fuel in the magazine.

During operation of the heater, air is drawn from the secondary chamber through the passageways in the bridge members 58 and discharged into the lower portion of the flue ducts to further promote efficient combustion, the amount of air admitted to the secondary chamber being regulated responsive to draft acting upon the damper 29. After the fuel burns in the fire-pot, the ashes drop into the ash-pan and coked fuel gravitates into the fire-pot to maintain the fire while the fuel in the upper portion of the magazine follows into the coking space.

From the foregoing it is obvious that I have provided a heater construction designed for more efficient control of combustion and which provides a heater of the magazine type having longer life for the reason that the parts which are subject to heat are located in heat exchange relation with the portions of the air supply, thereby reducing temperature of the parts and effecting preheating of the combustion supporting air.

It is also obvious that the invention is particularly adapted to modern shape and that the corners provide the vertical ducts through which products of combustion are discharged from the heater.

What I claim and desire to secure by Letters Patent is:

1. A heater of the character described including, a substantially rectangular jacket, a grate basket supported in the jacket including a substantially rectangular plate portion supporting a fire-pot, L-shaped ducts having connection with the fire-pot and opening through the plate portion within the corner of said jacket, a secondary air chamber encircling the grate basket, means for admitting air from the secondary chamber into the L-shaped ducts, a refractory liner supported above the grate basket and having portions spaced inwardly from corners of the jacket for providing vertical flue ducts in connection with said L-shaped ducts, and secondary air supply ducts connected with the secondary air chamber and located in heat exchange relation with the flue

ducts and discharging at the upper ends of said last named flue ducts.

2. A heater of the character described including, a substantially rectangular jacket, a grate basket supported in the jacket including a substantially rectangular plate portion supporting a fire-pot, L-shaped ducts having connection with the fire-pot and opening through the plate portion within the corner of said jacket, a secondary air chamber surrounding the grate basket, means for admitting air from the secondary chamber into the L-shaped ducts, and a refractory liner supported above the grate basket and having portions spaced inwardly from corners of the jacket for providing vertical flue ducts in connection with said L-shaped ducts.

3. A heater of the character described including, a substantially rectangular jacket, a grate basket supported in the jacket including a substantially rectangular plate portion supporting a fire-pot, ducts having connection with the fire-pot and opening through the plate portion within the corners of said jacket, bridge members spanning said ducts, said bridge members, each having a passageway for flow of air to reduce the temperature of said members, and a refractory liner supported on said plate portion and said bridge members and having portions spaced inwardly from the corners of the jacket for providing vertical flues in connection with said ducts.

4. A heater of the character described including, a substantially rectangular jacket, a grate basket supported in the jacket including a substantially rectangular plate portion supporting a fire-pot, ducts having connection with the fire-pot and opening through the plate portion within the corners of said jacket, bridge members spanning said ducts, each having a passageway for flow of air through the bridge members to reduce the temperature thereof, a refractory liner supported on said plate portion and said bridge members and having portions spaced inwardly from the corners of the jacket for providing vertical flues in connection with said ducts, and a secondary air chamber in heat exchange relation with the grate basket to reduce temperature of said basket and having connection with said air passage and to supply said air for the bridge members.

5. A heater of the character described including, a substantially rectangular jacket, a grate basket supported in the jacket including a substantially rectangular plate portion supporting a fire-pot, ducts having connection with the fire-pot and opening through the plate portion within the corners of said jacket, bridge members spanning said ducts and having an air flow passage, a refractory liner supported on said plate portion and said bridge members and having portions spaced inwardly from the corners of the jacket for providing vertical flues in connection with said ducts, a secondary air chamber in heat exchange relation with the grate basket to reduce the temperature of said basket and to supply said air for the bridge members, and secondary air ducts connected with the secondary air chamber and having connection with the upper ends of the flue ducts.

6. A heater of the character described including, a substantially rectangular jacket, a grate basket supported in the jacket including a substantially rectangular plate portion supporting a fire-pot portion, L-shaped ducts having connection with the sides of the fire-pot and opening through the plate portion within corners of said

Jacket, and a refractory liner supported on said plate portion and providing a fuel magazine above said grate basket, said liner having portions spaced from said corners of the jacket for providing flue ducts coextensive with the magazine at said corners.

7. A heater of the character described including a substantially rectangular jacket, a grate basket supported in the jacket including a substantially rectangular plate portion supporting a fire-pot portion, L-shaped ducts having connec-

tion with the sides of the fire-pot and opening through the plate portion within corners of said jacket, a refractory liner supported on said plate portion and providing a fuel magazine above said grate basket, said liner having portions spaced from said corners of the jacket for providing flue ducts coextensive with the magazine at said corners, and said liners having openings connecting the magazine with said flue ducts.
